UNITED STATES PATENT OFFICE.

HECTOR RABEZZANA, OF FLINT, MICHIGAN, ASSIGNOR TO A C SPARK PLUG COMPANY, OF FLINT, MICHIGAN.

VACUUM TANK.

Application filed January 4, 1926. Serial No. 79,109.

This invention relates to an improved arrangement for vacuum tanks. In common with other such tanks as used in connection with internal combustion engines, my invention uses suction to draw fuel from a main reservoir to a tank from which it is discharged by gravity to the carburetor. The tank is comprised of a valve chamber and a storage chamber. The valve arrangement is controlled by a float such that when the float is low the outlet from the valve chamber to the storage chamber is closed, and suction is then applied from the intake manifold to the valve chamber so as to draw fuel from the main reservoir to the valve chamber. As the valve chamber fills the valve, by a snap action, closes the manifold connection, opens an air vent, and allows the collected fuel to flow to the storage chamber through a valve simultaneously opening thereinto from the valve chamber.

One object of my invention is to use porcelain for the valve seats and the valves both at the connection with the pipe leading to the manifold and with the outlet from the valve chamber to the storage chamber.

A further object consists in a simple yet effective means for applying the movement of the float to the actuation of the valves.

Another object is the positive and simultaneous operation of the two valves, the suction inlet valve and the gasoline outlet valve, by means connecting the same.

A still further object is the provision of oscillatory valves and a connecting stem therefor rotated by a spring snap action.

With these and other objects in view, the invention may be embodied in various structural forms of which the one shown in the accompanying drawing and herein described is considered to be the best.

In the drawing:

Figure 1 is a vertical section through a vacuum tank disclosing my invention. Figure 2 is a horizontal section on line 2-2, Figure 1. Figure 3 is a section similar to Figure 1, parts however being broken away, showing the operative mechanism, in a different position. Figure 4 is a horizontal section on line 4-4 Figure 1. Figure 5 is a similar section on line 5-5 Figure 1. Figure 6 is a detail of the lower valve as seen from line 6-6, Figure 1.

Referring for a complete description to the drawing, numeral 1 represents a tank having

an upper part 2 and a lower part 3, each cylindrical in form and the two united by the overlapping portion 4 to make the complete tank. Centrally disposed at the end of the upper section is a recess 5, and extending above the recess is an opening 6. This extended end of the upper member is threaded as at 7 for the attachment thereto of a conduit leading to the intake manifold of the motor. In the shoulder at the recess is shown a vent at 8. At one side of the recess is an opening 9 over which is secured a threaded connection 10 by means of rivets 11, this connection serving for attachment of the pipe leading from the main gasoline tank. One of the rivets 11 is made use of to secure a baffle 12 which extends under the opening 9 and diverts the fuel entering through the connection 10 from falling upon the float. At the lower end of the cylindrical member 3 is a recess 13. This recess terminates in a reduced extension 14 having a threaded connection with the storage chamber 15.

Within the recess 5 is a porcelain valve seat 16. This valve seat has a passageway 17 extending therethrough and communicating with the opening 6, and with the intake manifold. The porcelain valve seat has a second opening 18 which registers with the vent 8 described above. Located within the second mentioned recess 18 is a porcelain valve seat 19 extending through which are passageways 20' which affords communication at times between the chamber 1 and the reservoir 15.

Numeral 20 represents a porcelain valve mounted for oscillation adjacent the lower face of the porcelain valve seat 16. It has a passage 21 extending therethrough which at times is made to register with passageway 17 of the valve seat. It also has a passageway 22 extending therethrough which at times registers with passageway 18 of the valve seat. Numeral 23 is used to designate a second porcelain valve mounted for oscillation on the valve seat 19 at the lower end of the chamber. This valve 23 having passages 24' which register at times with passage 20' for permitting the gasoline and chamber 1 to flow into reservoir 15.

For the purpose of simultaneously oscillating the two valves 20 and 23 I make use of the following arrangement. A stem 24 is journalled for oscillatory movement in central openings 25 in each of the valve seats.

This stem passes through central openings in the valves. Valve 20 is fixably secured to the stem by pin as shown at 26. Near the upper end of the stem 24 are radial arms 27 which are bent back and have legs 28 extending therefrom in a direction parallel to stem 8 and enter apertures 29 in the valve 20. A somewhat similar arrangement is shown at the lower end of the stem where there are 10 radial arms 30 and legs 31 entering the apertures 32 in the valve 23. Surrounding the stem between the valve 23 and the radial arms 30 is seen a coil spring 33. This coil spring functions to hold the valve 23 against its seat 19 and also to hold valve 20 against its seat 16. Extending transversely across the upper part of the chamber one on each side of the stem 24 are two pivot rods 34. Pivoted on each of these rods are elbow 20 levers 35. These levers are arranged side by side in opposed relation, as will be readily seen from examination of Figure 1 or Figure 3. The upper ends of the levers engage the opposite radial arms 27. The other 25 arms of the levers are connected by flat springs 36 with projections 37 extending divergently upward from a float 38, which float, as will be seen, is arranged to reciprocate in the valve chamber 1 and to be guided along the stem 24. Convenient means must be provided to limit the movements of the levers 35 in each of two directions. This may be done in other ways but a convenient way is shown, consisting in providing each 30 lever with a slot 39 engaging over the pivot rod 34 of the other lever. The position of parts 37, 36 and 34 is such that the point of connection of the yielding member 36 with the float projection 37 moves through 35 a plane defined by the transverse pivot 34 of a lever and the point of connection between that lever and the spring arms 36.

It is believed that the operation of the device will be understood without extended 40 explanation. In Figure 1. the parts are represented as having the position wherein the float is low in the tank and the passageway to the manifold is open. Under these circumstances, the engine being running, suction of the manifold withdraws air from tank 1 and admits fuel through opening 10. Under these circumstances it will be noticed that the opening at the bottom of the tank is closed. As the float rises, the inner ends 45 of yielding members 36 tend to rise but because of the engagement of the slots with the abutments 34 the levers cannot swing and the spring becomes bowed. When however, the outer ends of spring members 36 reach 50 a point above a plane determined by the lever pivots 34 and the connections of the levers with the arms 36 the spring straightens out, oscillates stem 24 and the connected valves whereupon the suction intake is closed, the air vent is opened and the fuel 55

outlet to the reservoir 15 is also opened. As the fuel flows out into reservoir 15 the float falls the spring members 36 become bowed until their extremities pass the plane above indicated, whereupon the valve position is 60 reversed. This process continues during the operation of the engine.

A further advantage consists in the use of porcelain for the valve and valve seats. It has been found that the porcelain, when 65 wet, makes an excellent seal.

I claim:

1. In a float chamber having an opening therein, a float, a fluid outlet, valves controlling said opening and outlet, means connecting said valves, means connecting said float to said connecting means whereby said valves are oscillated upon the reciprocation of the float. 80

2. In a float chamber, a float, a suction opening, a fluid outlet, valves for said opening and outlet, means connecting said valves for simultaneous oscillation, yielding means connecting said float and said connecting means to oscillate the valves. 85 90

3. In a vacuum tank having an opening containing a valve seat, an oscillating valve therefor, a lever, means connecting one lever arm with the valve at one side of its center of oscillation, a reciprocating float, yielding means connecting the other lever arm with the float, the parts being so positioned and proportioned that the yielding means acts with a snap action. 95

4. In a vacuum tank having an opening, an oscillating valve therefor, a reciprocating float, opposed levers, the pivot of each lever limiting a movement of the other lever, yielding means connecting an arm of each lever with the float, means connecting the opposite lever arms with the oscillating valve at opposite sides of the center of oscillation. 100 105

5. In a vacuum tank having an opening, an oscillating valve therefor, a reciprocating member, a lever within the tank having a fixed pivot transversely positioned, means to limit the swinging of the lever, means connecting the lever to the oscillating valve to oscillate the latter, yielding means connecting the opposite arm of the lever to the reciprocating member, the construction being such that the point of attachment of the yielding means and the reciprocating member crosses the plane defined by the transverse pivot and the point of connection of the yielding means and lever to thereby swing the lever and oscillate the valve. 110 115 120

6. The combination recited in claim 5 together with an oppositely positioned oscillating valve to control a fluid outlet, means connecting the two valves for simultaneous oscillation. 125

7. A combination as set forth in claim 5, together with an oppositely positioned oscillating valve, means connecting the two 130

valves for simultaneous oscillation, an abutment on the connecting means, and yielding means between the abutment and the second mentioned valve.

5 8. In a vacuum tank having oppositely disposed openings, an oscillating valve for each opening, means connecting the two valves for simultaneous oscillation, a float, yielding means operable upon the reciprocatory movement of the float to oscillate the valves.

10 9. The combination as set forth in claim 8 wherein the valves are oppositely opened and closed and wherein the closure of one valve is associated with a simultaneous air

15 vent therethrough.

10 10. In a float chamber having an opening at opposite ends, a valve seat at each opening, a rod extending through the chamber and journaled for oscillation in the valve 20 seats, valves on the rod mounted to oscillate therewith, there being openings in the seats and valves in position for registration in predetermined valve positions.

11. A combination as set forth in claim 25 10 together with a float, means connecting the float and oscillating rod to effect a snap oscillation of the rod and valves upon the oscillation of the float to predetermined positions.

20 12. In a float chamber having opposite

openings, a valve seat in each opening, an oscillating valve adjacent each valve seat, each valve and seat constructed with passages for registration, rod means connecting the said valves, spring means in abutment 35 with said rod and one of said valves to seat both valves firmly against their seats.

13. In a float chamber, a reciprocating float, a longitudinal extending valve oscillating rod along which the float reciprocates, 40 means connecting the float and rod to oscillate the latter in opposite directions as the float reaches opposite extremities of its reciprocation.

14. In a vacuum tank having an opening, 45 an oscillating valve therefor, two pivot rods, opposed levers one pivoted on each rod and each rod limiting the movement of the opposite lever, means connecting the levers to the valve on the opposite sides of its center of oscillation, yielding means connecting the other arms of the levers to the float, the construction being such that the point of attachment of the yielding means to the float pass through the plane defined by the pivots of 50 the levers and the point of attachment of the yielding means thereto to insure a snap opening and closing action of the valve.

In testimony whereof I affix my signature.
HECTOR RABEZZANA.
